UNITED STATES PATENT OFFICE.

IRA E. BURKETT, OF MACON, GEORGIA, ASSIGNOR TO SCHOFIELD-BURKETT CONSTRUCTION COMPANY, OF MACON, GEORGIA, A CORPORATION OF GEORGIA.

COMBINED SCRAPER AND DUMPING DEVICE.

Application filed September 11, 1922. Serial No. 587,411.

To all whom it may concern:

Be it known that I, IRA E. BURKETT, a citizen of the United States, residing at Macon, in the county of Bibb and State of Georgia, have invented certain new and useful Improvements in Combined Scraper and Dumping Devices; and I do hereby declare the following to be a full, clear, and exact description of the invention, such as will 5 enable others skilled in the art to which it appertains to make and use the same.

This invention relates to excavators, and more particularly to a distantly controlled combined scraper and dumping device for 15 use in connection with engineering projects involving the excavation of large or extended areas where it is convenient or necessary to convey, distribute and dump dirt or gravel to and from points remote from the 20 source of locomotive power and control, such as: grading extensive areas, levee construction or repair, railroad cuts and embankments, canal construction and the like.

The object of my invention is to provide a 25 device of the character referred to in which an ordinary dirt scraper may be utilized to collect dirt or gravel from any desired point and convey and dump the same at any point within or outside the excavation or grading 30 areas either to distribute the same over such area, or to dump it into suitable hauling vehicles for removal.

Further objects of my invention are to provide a device of the character referred 35 to which will be simple, durable and inexpensive in construction, use and transportation from place to place, in which an ordinary scraper may be readily connected or disconnected at the will of the operator.

The specific purpose of my invention is to 40 provide mechanical means for drawing an ordinary scraper forwardly along a line from a variably fixable point to fill the scraper and afterward convey it to any desired point along such line for dumping to provide mechanical means for dumping the 45 scraper at any point along the line of its forward movement over the ground and to provide mechanical means for returning the 50 scraper by drawing it backwardly for repeated refilling and dumping at any point or points along its line of progressive movement over the surface of the ground without requiring manual control for so doing.

55 My invention will first be hereinafter

more particularly described, with reference to the accompanying drawings, which are to be taken as a part of this specification and then pointed out in the claims at the end of the description.

In said drawings, Fig. 1 is a perspective elementary view of my device in position for use, illustrating the fundamental arrangement of the various elements and showing the means under power control for drawing the scraper forwardly or backwardly and the means for dumping the scraper at will. In this view the scraper is shown in loading position as it is being drawn forwardly to be afterward conveyed to the desired point 60 for dumping;

Fig. 2 is a side elevational view of the device illustrating a convenient arrangement of the various elements for levee construction, the scraper and standing line being 65 shown in full lines in dumping position and in dotted lines in conveying position;

Fig. 3 is a side elevation of the scraper in loading position, the standing line being 70 slack;

Fig. 4 is a side elevation of the scraper in hauling position; and

Fig. 5 is a plan view of the same.

Referring to the drawings, in which like reference numerals are used to denote corresponding parts throughout the several views, 75 1 denotes an ordinary steam engine or locomotive adapted under suitable lever control by an operator to actuate associated rotatable cable drums 2, 3 and 4, each of which are provided with the usual dog and ratchet locking means and with the usual brake devices applied thereto for a well known purpose. An ordinary scaffold 5 of any preferred design is erected conveniently adjacent thereto or upon a suitable platform therewith, which may be mounted on railroad trucks, as illustrated in Fig. 2, for convenience of transportation, or expeditious and rapid transfer from place to place. The scaffold 5 is provided with pulleys 6, 7 and 8, and may be adequately braced by suitable guys, (not shown). Referring particularly to Fig. 1, a tension controllable standing line or cable 9 is secured at one end to and wound upon the drum 2, its other or free end being passed over the uppermost pulley 6 on the scaffold 5 and from thence to a fixture or stake 10 to which it is secured. The cable 9 may be drawn taut or allowed to suspend 80

slack by virtue of its own weight between the top of the scaffold 5 and the fixture 10, simply by winding or unwinding the cable over the drum 2, the purpose therefore to be 5 hereinafter more particularly defined.

To the forward end of an ordinary scraper 11, preferably by means of divided chain sections, the ends of which are secured to suitable reinforcing bracketed plates provided on either side of the scraper, one end of a hauling or pulling cable 12 is attached, said cable being passed over the pulley 8 on the scaffold 5 and having its other end wound upon and secured to the drum 4, so 10 that when the drum 4 is caused to rotate in such way as to wind the cable 12 thereupon, the scraper 11 will be drawn forward to load with earth and afterward convey the load to the desired point for dumping.

20 To the upper side sections of the scraper 11, the respective extremities of an inverted U-shaped bail are pivotally secured, the central part thereof being adapted to pivotal connection with one end of a suitable rod, the opposite end of the latter being pivotally connected to an actuating hand lever 11^a, by which the bail may be caused to move forward or backward beyond the balancing center of the scraper. A reach or balance cable 11^b, is attached at one end to the top center of the bail, and at its other end to the hauling or pulling line 12, at a point forward of the latter's point of attachment with the scraper 11. It will be readily understood that by means of the lever 11^a, the bail may be drawn backward beyond the balancing center of the scraper, thus causing the reach or balance cable 11^b to become taut and pull the forward end of the scraper down beyond dead center in loading position, illustrated by Fig. 3, so that its spiked edge or bottom will be forced to dig into the ground as the scraper is drawn forwardly by the cable 12 to load the same. 30 After the scraper has become filled with earth, the hand lever 11^a is manipulated to move the bail forward of the balancing center thereby relieving the tension on the reach cable 11^b, allowing it to become loose or slack and permitting the scraper to assume the hauling position illustrated in Fig. 4 with its forward end or bottom edge slightly above the surface of the ground so that it may be drawn forwardly to convey the load 40 to the dumping point without becoming snagged by the undulations of the ground or by small rocks or other impediments embedded in the soil.

50 The scraper 11 is also preferably provided with a rearwardly extended Y-shaped frame bar, the oppositely disposed ends of which are secured to the rear side sections of the scraper. To the central extremity of the frame bar, a suspension cable or chain 65 13 is attached, the opposite end of the chain

being connected to a pair of traveling pulleys or pulley carriage 14, the latter being adapted to move along the length of the suspended standing cable 9 with relation to the scraper as it is drawn forwardly or rearwardly, the chain 13 being shorter than the measured height of the cable 9 above ground when taut. To the rear portion of the scraper 11 by suitable attachment means, one end of a backing cable 15 is fastened, said backing cable being passed over pulleys 16 and 17, the latter being secured to a suitable fixture 18 which may be either an ordinary stake driven in the ground, as illustrated in Fig. 1, or may be a stanchion or post, as illustrated in Fig. 2, suitably secured and braced by guys 19 to a push car 20. The cable 15 is passed from the pulley 17, over the pulley 7 on the scaffold 5, and is wound upon the drum 3, its end being securely fastened thereto. It will be readily understood that when the drum 4, upon which the pulling cable 12 is wound, is allowed to run free, and spend the cable, the drum 3 may be rotated to wind the backing cable 15 thereupon, thus drawing the scraper backwardly into position for reloading and conveyance to the point of dumping.

The operation of my improved combined 95 scraper and dumping device is as follows:

The drum 2 upon which the standing cable 9 is wound is allowed to run free, permitting the cable to suspend slack by virtue of its own weight between the pulley 6 and the fixture 10. The scraper 11 is drawn backwardly to the point (under the slack cable 9) at which it is desired to begin loading, by winding the backing cable 15 upon its drum 3, simultaneously allowing the drum 4 to run free to spend the pulling cable 12 as necessary. When the scraper 11 has been thus drawn to the point of loading, brakes are applied to the drum 4, and the ratchet locking means should be set to prevent slippage of the drum, while drum 3 should be set to run free and spend the backing cable 15 as necessary. A ground operator then pulls the hand lever 11^a so that the reach cable 11^b on the scraper will be tightened to draw the scraper in loading position when a pull is exerted on the pulling cable 12. The drum 4 is then caused to rotate by the engine operator, to wind the pulling cable 12 thereon, whereupon the scraper will be drawn beyond dead center and will scrape up a load of dirt or gravel in the well known manner. When the scraper has been thus loaded, the ground operator pushes the hand lever 11^a to loosen the reach cable 11^b, so that the scraper will assume its hauling position as it is drawn forwardly by the pulling cable 12 to be conveyed to the point for dumping. As the scraper moves forward the backing cable 125 130

15 is allowed to spend freely therewith from the drum 3. When the scraper reaches the point for dumping brakes are applied to the drum 3 and drum 4 is stopped, thus 5 bringing the scraper to rest. Drum 2 is then caused to rotate by the engine operator, to wind the standing cable 9 thereon to taute the same. As the cable 9 begins to tighten, the suspension cable or chain 13 10 fastened between the scraper and the pulley carriage 14, will become taut and lift the rear of the scraper free from the ground. When the cable 9 becomes taut or nearly taut, the cable or chain 13 will consequently 15 hoist the scraper entirely clear of the ground and completely upset it, thus effectually dumping the scraper, whereupon the drum 2 is allowed to run free relieving the tension on the standing cable 9 and loosening 20 the same permitting it to assume its normal slack state so that the scraper will be lowered again to the ground. The drum 4 is then allowed to spend the pulling cable 12 as the drum 3 is again rotated to wind 25 the backing cable 15 thereon by which means the scraper is drawn backwardly to the point for reloading. This operation is repeated until the proper depth of excavation 30 has been effected, the earth being thus loaded, distributed or dumped at any desired point between the fixture 10 and the scaffold 5. The area of excavation operation may be broadened or expanded at will merely by moving the fixtures 10 or 18 35 either by lengthening or shortening the measured distance between such fixtures and the scaffold, or by moving the fixtures one way or the other in an arc with the scaffold as a center. If preferred, as a matter of 40 expediency, the free end of cable 9 may be secured to the push car 20, so that the line of scraper operations may be readily changed simply by pushing the car forward or backward the desired distance, or referring to Fig. 2, the platform on which the engine and scaffold are mounted, may be moved to establish a new line of operations. 45

Should it be desired to cart the earth away from the excavating area, an inclined runway 5^a may be utilized, up which the scraper may be drawn and upset, to unload into a dump cart or car drawn in position thereunder where it will receive the load.

Various changes may be made in the details and arrangement of parts shown and described without departing from the spirit and scope of my invention, and I do not desire to be restricted in the appended claims to the specific structure shown.

Having thus described my invention, what I claim as new and desire to secure by Letters-Patent of the United States is:

1. In a combined loading and dumping device, a scraper; pulling cables having respective ends attached to said scraper for

drawing the latter forwardly and backwardly; a normally slack cable elevated above the surface of the ground and secured at one end to a fixture; means acting on said last named cable independently of said pulling cables for suspending the scraper therefrom, by which the scraper will be lifted above the ground when the cable is drawn taut; a series of independently rotatable cable drums mounted upon a platform which is supported on wheels and movable transversely of the line of movement of said pulling cables; and a power device for selectively actuating the drums, each of said cables having their opposite ends wound upon a drum by which the respective cables are independently controlled. 70

2. In a combined loading and dumping device, a scraper; a pulling cable having one end attached to said scraper for drawing it forwardly and a backing cable having one end attached thereto for drawing it rearwardly; a normally slack cable suspended above the surface of the ground and secured at one end to a fixture carried by a platform which is mounted on wheels and movable transversely of the line of movement of the cable; a pulley movable along the length of said normally slack cable; a normally slack means for suspending the scraper from said pulley, by which the scraper will be hoisted above the ground when said cable is drawn taut independently of said pulling and backing cables; drums upon which the respective opposite ends of said cables are independently wound, said drums being mounted upon a supporting structure which is mounted on wheels and movable transversely of the line of movement of said cables; and means for independently rotating and selectively controlling said drums. 90

3. A combined loading and dumping device comprising a scraper having an arm projecting rearwardly and upwardly from its rear end, a normally slack cable having one end fixed at a distance from said scraper and the other end secured to a drum on which it may be wound for tightening and loosening said cable, a flexible connection between said cable and said inclined arm including a pulley arranged to travel along said cable, a pulling cable having one end secured to the front end of said scraper and the other end secured to a pulley over which it may be wound for drawing the scraper forwardly, a haul-back cable having one end secured to the rear end of said scraper and the other end secured to a pulley over which it may be wound for drawing the scraper rearwardly, said pulleys being arranged upon a supporting structure which is mounted upon wheels and movable transversely of the line of movement of said cables, and means for independently rotating 110

120

125

130

4
said drums; said scraper having a forwardly and backwardly swinging bail thereon, a flexible connection between the upper end of said bail and said pulling cable, a lever 5 pivoted on the rear end of said cable and a rod connecting said lever and bail, whereby the scraper may be held in operative position with its cutting edge lowered and its rear end raised, and its position shifted, so 10 as to raise its front end and lower its rear

end when said lever is shifted to throw said bail forward, thus permitting the loaded scraper to be drawn with its intermediate bottom surface resting on the ground.

In testimony whereof I affix my signature in the presence of two witnesses.

IRA E. BURKETT.
